(57) **CLAIM**

The ornamental design for a light fixture, as shown and described.

DESCRIPTION

FIG. 1 is a top, right and front perspective view of the first embodiment of the light fixture;

FIG. 2 is a bottom, left and rear perspective view of the light fixture of FIG. 1;

FIG. 3 is a front elevation view of the light fixture of FIG. 1; FIG. 4 is a right side elevation view of the light fixture of FIG. 1 and the left side elevation is a mirror image;

FIG. 5 is a rear elevation view of the light fixture of FIG. 1;

FIG. 6 is a top view of the light fixture of FIG. 1;

FIG. 7 is a bottom view of the light fixture of FIG. 1;

FIGS. 8-14 illustrate another embodiment of a design for a light fixture wherein

FIG. 8 is a top, right and front perspective view of the light fixture;

FIG. 9 is a bottom, left and rear perspective view of the light fixture shown in FIG. 8;

FIG. 10 is a front elevation view of the light fixture as shown in FIG. 8;

FIG. 11 is a rear elevation view of the light fixture as shown in FIG. 8;

FIG. 12 is a right side elevation view of the light fixture as shown in FIG. 8; and the left side elevation is a mirror image;

FIG. 13 is a top view of the light fixture as shown in FIG. 8;

FIG. 14 is a bottom view of the light fixture as shown in FIG. 8.

The broken lines in FIGS. 8-14 are for illustrative purposes only and form no part of the claimed design.
